To all whom it may concern:

Be it known that I, Louis J. Golden, a citizen of the United States, residing at Highland Park, Lake County, Illinois, have invented a new, original, and ornamental Design for a Juvenile Shoe,
of which the following is a specification, reference being had to the accompanying drawing, as forming a part thereof.

Figure 1 is a perspective view of one side of a shoe showing my new design.

Figure 2 is a perspective view of the other side of the shoe shown in Figure 1.

I claim:

The ornamental design for a juvenile shoe, as shown.

LOUIS J. GOLDEN.
